AMMUNITION-BOX.

1,120,244.

Specification of Letters Patent.

Patented Dec. 8, 1914.

Application filed June 25, 1912. Serial No. 705,715.

To all whom it may concern:

Be it known that I, FRIEDRICH SACHTLEBEN, residing at Essen-on-the-Ruhr, Germany, a subject of the Emperor of Germany, have invented a certain new and useful Improvement in Ammunition-Boxes, of which the following is a specification.

This invention relates to boxes for artillery ammunition and aims at the use of only one box, utilizing the space in the best possible way, either for transportation of projectiles, together with the powder charges belonging thereto, or for transportation of made-up ammunition. Naturally the boxes are intended for projectiles and powder charges or made-up ammunition for one and the same gun. Two different kinds of ammunition boxes have heretofore been necessary for transportation of ammunition.

One embodiment of the invention is represented in the drawing where a portable ammunition box is shown which is intended either for the transportation of three mine shells, together with the necessary powder charges or for the transportation of four shrapnels in their cartridge-cases.

In Figure 1 is shown a front elevation partly in section of the ammunition box with contents. Fig. 2 a top view of the same ammunition box empty and in section on lines 2—2 of Fig. 1.

The ammunition box A provided with the lid A¹ wherewith it can be closed, is divided into two chambers A² and A³ by a partition B. The chamber A² shown to the left of the drawing is intended to receive either one mine shell C and three cartridges D for the shell, or to receive two shrapnels in cartridge-cases E. With this object in view three frames F are arranged at different heights in the chamber A², which frames are each provided with a circular collar-shaped opening f¹ and a square collar-shaped opening f², see particularly Fig. 2.

The openings f¹ on each of the frames F lie exactly over each other as also the openings f². The size of the uppermost of the circular openings f¹ corresponds to the diameter of the cartridge case E of the shrapnel, while the middle and lower of these openings f¹ have a measurement that corresponds to the caliber of the body of the projectile, so that the openings f¹ might serve as a bearing for the shrapnel-cartridge. The case of the shrapnel-cartridge and the gas

band of the same are in Fig. 1 denoted by dot and dash lines; the rest of the shrapnel which is identical with the forward part of the mine-shell is denoted by solid lines. The openings f¹ may also, as has been shown in Fig. 1 by solid lines, receive a mine-shell C instead of the shrapnel-cartridge E.

The square shaped openings f², which are all of the same size, serve as bearings for a receptacle G provided with two handles g¹ which may contain either three powder charges D or one shrapnel-cartridge E. For carrying the powder charges are provided three openings g², one above the other at one of the narrow sides of the receptacle G, which openings are made to suit the forward diameter of the case of the powder charge; and at the opposite narrow side are provided three openings g³, made to suit the rear diameter of this case. The arrangement of these parts is such that the powder charges when resting in the bearings formed by the openings g² and g³, will abut against the partition B with the bottom d¹ of the charge case D. A lid H grips over each of the openings g²; and these lids are so shaped, as will be seen from the drawing, that they abut against the cover d² of the charge case D, when said cases are placed in their bearings g², g³, so that they are secured against displacement, Fig. 1. In order to place a shrapnel-cartridge E, in place of the powder charge cases D (the former shown in Fig. 1 by dot and dash lines) in the receptacle G, this receptacle is provided at the top with a circular opening g⁴, the diameter of which is suited to the cartridge-case. Furthermore there are provided, between the bearings g² and g³, circular contractions g⁵ in the receptacle G for the powder charges, the inner diameters of which correspond to the caliber of the projectile. As will be seen from the drawing, the bearing space of the shrapnel-cartridge E penetrates the bearing spaces of the powder charges D.

The chamber A³ of the box shown on the right hand side of the drawing, contains, at the same level as the frames F, three other frames J, which are each provided with two circular openings i¹. These are shaped and arranged in the same manner as the circular openings f¹ of the frame F, so that the chamber A³ may receive either two mine shells or two shrapnel-cartridges. As will

be evident from the above, either three case-shots, together with the cartridges belonging thereto may be packed in the described ammunition boxes (in the bearings f^1 , i^1 and g^2 , g^3 respectively) or else four shrapnels with cartridge-cases (in the bearings f^1 , g^4 , g^5 and i^1).

The powder charge bearings g^2 , g^3 and the cartridge bearings g^4 and g^5 need not necessarily be arranged in a removable receptacle of the ammunition box. It might be mentioned, that if the chamber A^3 for the ammunition box were situated to the left of the chamber A^2 , instead of to the right thereof (as in the drawing), it would only be necessary to have the partition B removable in order to gain admittance to the powder charges D .

As the receptacles G have been made removable, as represented in the embodiment of the invention shown in the drawing, for the obvious reason of having the powder charges accessible, this object may equally well be attained, by this second embodiment, if the bearings g^2 , g^3 , g^4 and g^5 were made fast in the ammunition box.

I claim—

1. An ammunition box having a chamber with a set of bearings adapted to receive an assembled projectile and cartridge, and in the same chamber a plurality of secondary

sets of bearings, each secondary set adapted to receive a single cartridge, the axis of each secondary set of bearings running transversely to the axis of the first set of bearings, in combination with a third set of bearings, said third set being adapted to hold either a projectile or an assembled projectile and cartridge.

2. An ammunition box having a chamber with a set of bearings, adapted to receive an assembled projectile and cartridge, and in the same chamber a plurality of secondary sets of bearings, each secondary set adapted to receive a single cartridge, the axis of each secondary set of bearings running transversely to the axis of the first set of bearings, said first-named set of bearings and said secondary sets of bearings being arranged in a receptacle inserted into the box and adapted to be lifted therefrom; in combination with a third set of bearings, said third set being adapted to hold either a projectile or an assembled projectile and cartridge.

The foregoing specification signed at Barmen, Germany, this 4th day of June, 1912.

FRIEDRICH SACHLEBEN. [L. S.]
